PUTTER HEAD

Robert W. Hyde, 1650 Colonial Drive, Cincinnati, Ohio

Filed Apr. 12, 1961, Ser. No. 64,754

Term of patent 14 years

(Cl. D34—5)

The fragmentary broken line showing of a shaft in the figures is for illustrative purposes only.

I claim:

The ornamental design for a putter head, substantially as shown and described.
